Lucian A. Sheldon, Schenectady, N. Y., assignor
to General Electric Company, a corporation of
New York

Application November 4, 1942, Serial No. 464,476

1 Claim. (Cl. 257—28)

The present invention relates to condenser boilers and like surface type heat exchangers such as are used, for example, in mercury power plants to condense mercury vapor exhausted from a turbine by transferring heat from the mercury vapor to a liquid such as water to be evaporated.

The object of my invention is to provide an improved construction and arrangement of condenser boilers and like heat exchangers of the type above specified which are simple and compact in construction and efficient in operation.

For a consideration of what I believe to be novel and my invention, attention is directed to the following description and the claims appended thereto in connection with the accompanying drawing.

In the drawing Fig. 1 illustrates a surface type heat exchanger embodying my invention; and Fig. 2 is a section along line 2—2 of Fig. 1.

The surface type heat exchanger illustrated in the drawing is particularly adapted as a condenser boiler for mercury power plants. The arrangement comprises a vertically disposed cylindrical shell 10 with a bottom 11 and a top 12. The shell 10 has an opening on one side intersecting with and fused to a flanged cylinder 13, which latter forms an extension of and is fastened to a turbine casing 14 forming part of a mercury turbine which includes a rotor 15 having a bucket wheel 16 secured to an overhung shaft 17 with a row of buckets 18 adjacent an opening or inlet 19. This opening is formed between the inner surface of the flanged cylinder 13 and a disk 20 adjacent the disk of the bucket wheel 16 and supported on the flanged cylinder 13 and the shell 10 by a horizontal web or partition 21 and a vertical web 21a fused to the disk 20 and to the inner surfaces of the extension 13 and the shell 10. The webs 21 and 21a while acting to support the disk 20 and to reinforce the shell structure also serve as guides for elastic fluid passing into the condenser and aiding uniformly to distribute the fluid therein. In addition the webs act as baffles to keep condensed mercury flowing along the tubes from being sucked into the center of the wheel and then thrown out tangentially, thus cutting the last stage buckets on the turbine.

The cooling arrangement or, from another viewpoint, the boiler means associated with the shell 10 comprises an elongated cylindrical drum 22 vertically disposed in the shell 10 and arranged somewhat off center in a direction away from the inlet for elastic fluid of the shell 10.

The drum 22 has a bottom projecting slightly out of the shell 10 and closed by a bottom plate 23, and a top portion projecting through and sealed to an opening in the top portion 12 of the drum. The top portion of the drum is closed by a closure plate 24.

A plurality of heat transfer tubes 25 are substantially uniformly distributed about the drum 22 inside the shell 10. Each tube has a lower bent portion 26 connected to a lower portion of the drum and an upper bent portion 27 connected to an upper portion of the drum. Liquid to be evaporated such as water is conducted to the drum by a conduit 28 arranged diametrically opposite the vapor inlet to the drum. The conduit 28 has a portion projecting through an opening in the shell 10 radially towards the drum 22 and sealed to an opening in the drum. The upper end portion of the drum 22 is connected to a conduit 29 for discharging vapor from the drum.

The arrangement includes means for removing non-condensables such as air from the shell. This means comprises a conduit 30 which has a portion 31 disposed within the liquid supply conduit 28. The inner end of the portion 31 is connected to branches 32 and 33 sealed to diametrically opposite openings in the conduit 28. The end portions of the branches 32 located outside the conduit 28 have perforations 34 for receiving non-condensables to be removed from the shell.

During operation the liquid such as water to be evaporated is supplied to the drum 22 through the liquid supply conduit 28 until the water in the drum has reached a level 35 somewhat below the connections of the drum to the tube end portions 27, thus filling the major portions of the tubes 25. Due to the eccentric arrangement between the shell 10 and the drum 22 with the tubes 25, vapor such as mercury vapor passed through the inlet of the shell is uniformly distributed among the passages formed between the spaced tubes 25. Heat is thus substantially uniformly transferred across the entire surfaces of the tubes 25. The heat transfer to the water in the tube causes evaporation of the water and the steam expelled from the tube end portions 27 into the drum 22 is discharged through the conduit 29. Mercury condensate in the shell collects in the bottom 11 and is discharged from the shell through a condensate discharge conduit 36 sealed to an opening in the bottom 11. The coolest region in the shell is formed substantially diametrically opposite the inlet of the

shell near the wall of the drum 22, that is, near a wall portion of the drum 22 facing away from the inlet of the shell 10. Air and other non-condensables mixed with the mercury vapor collect in this coolest region and are removed therefrom through the condensate removal means including the perforated branch conduits 32, 33.

Thus, with my invention I have accomplished an improved construction of condenser boilers in which the cooling tubes are symmetrically disposed about and connected to lower and upper portions of a drum. The cooling tubes are completely enclosed within the condenser shell. Both the drum and the shell are preferably cylindrical with the drum arranged off-center from the shell. The drum has a lower portion filled with liquid broadly constituting a lower liquid header connected to the lower ends of the tubes, and an upper portion connected to the upper ends of the tubes for receiving vapor therefrom and broadly constituting an upper or vapor header. By making such two headers, the lower or liquid and the upper or vapor header, in the form of a vertically disposed single drum a simple and compact structure is obtained, permitting liquid discharged into the vapor header to return directly through the drum into its lower portion or liquid header. The liquid level in the drum is maintained below the connection of the drum with the outlets of the tubes 25 to preclude reverse circulation of fluid through the tubes.

The non-condensable removal means are arranged in the coolest region in the shell and include a conduit partly enclosed within the li-

uid supply conduit to the drum, thus assuring effective cooling in the region of the perforated air removal conduit means.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

Condenser boiler comprising a vertically disposed cylindrical shell having a side wall with an opening for receiving vapor to be condensed, a vertically disposed cylindrical drum located in the shell with its centerline spaced from that of the shell in a direction away from said opening, a plurality of vertical heating tubes symmetrically disposed about the drum within the shell each having a lower end portion connected to a lower portion of the drum and an upper end portion connected to an upper portion of the drum, liquid supply and vapor discharge conduit means connected to the drum, the liquid supply conduit means comprising a conduit extending radially through the shell and connected to a portion of the drum substantially diametrically opposite from said opening, and a conduit for removing non-condensables from the shell having a portion located within the liquid supply conduit in the shell and a perforated extension connected to said portion and projecting from the liquid supply conduit in proximity of the drum.
